UNITED STATES PATENT OFFICE.

MARTIN L. NELSON, OF PARK RIDGE, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed March 9, 1925, Serial No. 14,001. Renewed September 21, 1928.

My invention relates in general to automatic telephone systems, but more particularly to such automatic systems as include a number of different offices or exchanges, commonly known as multi-office systems. A new piece of equipment or apparatus called a director has recently been developed for use in systems of this character, principally in order to handle the inter-office trunking on a more efficient basis. While the director trunking follows known practice to a large extent, it is much more flexible than methods formerly practiced. The introduction of the director opened up certain new lines of development in trunking and at the same time rendered possible a number of variations or modifications of known trunking arrangements which could not be used without it. The present application deals with certain improvements which I have made under the foregoing circumstances, and the object, therefore, may be stated to be a novel and improved trunking system for multi-office telephone systems in which directors are used.

The invention has a number of different aspects, or distinct features, which, however, can best be pointed out in the course of a more detailed description of the system in connection with the accompanying drawings.

The drawings, comprising Figures 1 and 2, show diagrammatically the inter-office trunking between five main offices and one sub-office, which are assumed to be part of a large multi-office net-work involving a much greater total number of offices, perhaps fifty or more altogether. Since the invention has to do only with the trunking, no circuits are shown, but reference is made to the following applications which disclose the circuits and apparatus which are suitable for use in the system herein described:

A. J. Ray Ser. No. 438,985, filed Jan. 21, 1921; T. G. Martin Ser. No. 392,943, filed June 30, 1920; R. G. Richardson and M. L. Nelson Ser. No. 538,551, filed Feb. 23, 1922; M. L. Nelson Ser. No. 719,719, filed June 13, 1924.

The drawings may now be described more in detail, reference being first had to the lay-out of the Midway office, Fig. 1. The reference letter A indicates a subscriber's station of the usual automatic type. At the Midway office, with which the substation

A is associated, the subscriber's line terminates in the usual line or trunk selecting switch L. A number of these line switches have common access to a group of first office selectors, such as the selector FS, which will be referred to hereinafter for convenience merely as a first selector. The trunk extending from the line switch bank to the first selector FS is in two sections, and at the junction of these sections a relay group is provided. This relay group is indicated in the drawing by the reference letters RG and its function, briefly stated, is to enable a director to be associated with the trunk while a connection is being set up thereover and to free the director and unite the two sections of the trunk line for talking purposes after the connection has been established. Directors suitable for use are disclosed in the two Nelson applications previously referred to herein, one of which shows complete circuits of a typical director, while the other shows the mechanical construction. The exact method employed for connecting a director with a trunk line when required is immaterial and several ways are known, but as illustrated herein each director is provided with a finder switch which has access to a number of first selector trunk lines. To explain this a little more fully, it may be pointed out that the trunk lines such as the one shown extending to the first selector FS are divided into groups, the number of trunk lines in each group depending upon the capacity of a finder switch such as F. For example, if the finder switches each have a capacity of twenty-five lines, then the trunk lines will be divided into groups of twenty-five each. Each of these groups of trunk lines is served by a group of directors, the number of which will depend somewhat upon traffic conditions, but which in any case will be much less than the number of trunk lines in a group. The foregoing arrangement is clearly illustrated in the drawing, in which the director D is indicated as having access to the trunk line extending to the first selector FS by means of the finder switch F and a branch of the trunk line extending downward from the relay group RG. This branch is shown indicated by two parallel lines, accessible to two wipers of the finder, because of the fact that it includes both incoming and outgoing circuits to and from the director.

100

105

110

The first selectors, such as FS, otherwise known as office selectors, are used to select trunk lines to the different offices of the system or local trunk lines, and in case the 5 total number of groups of trunk lines is within the capacity of a single selector, that is, not more than ten, only a single order of switches will be required. In other words, all the trunking outgoing from the 10 Midway office could be accomplished by means of first selectors only. In a large multi-office system, however, it will usually be the case that considerably more than ten groups of trunk lines are necessary, from 15 which it follows that second selectors will have to be used in addition to the first selectors. The number of groups of second selectors required will, of course, depend upon the number of groups of trunk lines. 20 The drawing indicates a group of second selectors accessible from the second level of the first selectors, one second selector, SS, being shown. These second selectors give access to ten groups of trunk lines, and if it 25 be assumed that the remaining levels of the first selectors are used for trunk lines also, then the total capacity will be nineteen groups of trunk lines. This can be increased to any reasonable extent by adding 30 additional groups of second selectors, each group added giving an additional capacity of ten groups of trunk lines while taking away one group at the first selectors, giving a net gain of nine groups.

35 The local trunk lines for the Midway office may be taken off from a level in either the first selectors or the second selectors, although it is preferable to use a level of the second selectors for this purpose in order 40 to save as many levels of the first selectors as possible for tandem trunking, as will be pointed out hereinafter. Accordingly, in the present case the local trunk lines are taken off from the fifth level of the second 45 selectors, one of these trunk lines being indicated in the drawing as extending to the thousands selector T. Following the usual practice, the thousands selectors have access to ten groups of hundreds selectors, such 50 as the selector H, and the hundreds selectors in each group have access to ten groups of connectors such as the connector C. The connectors, of course, will have access direct 55 to the subscribers' lines which are associated with the Midway office.

The trunks outgoing from the Midway office to other main offices include repeaters. According to the usual practice, if there are more than ten trunks in a group, secondary line switches may be used in order to give all the selector switches common access to all the trunks. This arrangement is indicated in the drawing, where it will be seen that the outgoing trunks from the sixth level 60 of the first selectors such as FS terminate

in rotary secondary line switches such as L⁵, which in turn have access to the outgoing trunks by way of repeaters such as R.

Trunk lines incoming to the Midway exchange terminate in so-called incoming 70 selectors, the banks of which are multiplied at the Midway office with the banks of the proper order of switches in such office, either the first or second selectors or the thousands 75 selectors, as the case may be. The drawings indicate a group of trunk lines incoming to the Midway office from the Main office, one of which trunk lines is shown as terminating in the incoming selector IS, the banks of which are multiplied with the banks of the thousands selector T. The incoming trunks from the sub-exchange Riverside do not terminate in incoming selectors as do the trunk lines from main exchanges, but terminate in line switches. This is shown in 80 the drawing where it will be seen that the trunk lines from Riverside to Midway come from the banks of secondary line switches such as L³ in Riverside, and terminate in line switches such as L' in Midway. The 85 latter line switches may be multiplied with certain groups of primary line switches, such as the line switches L and L', associated with substations A and A', respectively.

The lay-out of the Main office follows the same general plan that has been explained in connection with the Midway office, except for certain changes in the arrangement of the office and incoming selectors. In view 90 of this, the subscribers' lines and the directors are not shown, and the hundreds selectors and connectors have been omitted also, being precisely the same as illustrated in connection with the Midway office. The trunk line terminating in the first selector FS' is assumed to come from a relay group such as the relay group RG already described. The first selector such as FS' may have access to certain groups of direct trunks to other offices, although none are shown in the drawing. These selectors may also have access to one or more groups of second selectors, two such groups being indicated in the drawing, which shows a trunk line extending from the fifth level of the 105 first selector FS and terminating in the second selector SS', and also a trunk line extending from the first level of the first selector FS' and terminating in the second selector SS². The thousands selectors for the 110 Main office are reached by way of the first level of the latter group of second selectors. The incoming selectors in which the trunk lines from the Midway office terminate, one of these selectors being indicated by reference character IS², have their banks connected in multiple with the banks of the second 115 selectors SS', while the incoming selectors from the North and South offices, such as IS³ and IS⁴, respectively, have their banks 120

125 connected in multiple with the banks of the second selectors SS', while the incoming selectors from the North and South offices, such as IS³ and IS⁴, respectively, have their banks 130

connected in multiple with the second selectors SS². The reason for this particular arrangement will be pointed out more in detail hereinafter.

5 From what has been said in the foregoing in connection with the Midway and Main offices, the layout of the North, South and East offices, Fig. 2, will be readily understood as to its main features, and it will be
10 unnecessary to point out each of the various switches and specify their function. As in the case of the Main office, the subscribers' lines and line switches, the directors, the hundreds selectors and connectors have all been
15 omitted, and only the office, incoming and thousands selectors are shown. The arrangement of these switches is not precisely like that shown in connection with the Midway and Main offices, or either of them, but
20 follows the same general plan and the differences will be pointed out in connection with other matters shortly to be described.

The Riverside exchange, although it is given an office name or designation like a main exchange, is not a main office but is what is known as a sub-office and is subsidiary to the Midway office. The capacity of the Riverside sub-office is one-thousand lines, the particular thousand used being the fifth thousand of the ten different thousands which are part of the Midway office, this fifth thousand being used for the Riverside sub-office instead of being used in the main exchange.

35 One of the branch exchange sub-stations is indicated by the reference letter A², and the reference letter L⁴ indicates the individual line switch in which the line of this station terminates at the sub-office. Line-
40 switch L⁴, together with a number of other similar line switches, is given access to a group of so-called switching selector repeaters, one of which is indicated by the reference letters SSR. These switching selector repeaters may be of the type shown
45 in the application of Ray hereinbefore referred to. Associated with each switching selector repeater is a secondary line switch such as the line switch L³, by means of
50 which access is had to trunk lines extending to the main or Midway exchange. On the local level the switching selector repeaters such as SSR have access to hundreds selectors, such as the hundreds selector DH. These hundreds selectors are of the digit-absorbing or drop-back type—that is, they release after responding to the first digit. The hereinbefore mentioned application of Martin dis-
55 closes a suitable type of drop-back selector for use in this situation. The drop-back selectors, such as DH, have access to ten groups of connectors, such as the connector C', by means of which connections are com-
60 completed to the local lines in the sub-office.

The incoming trunks from the Midway office terminate in incoming selectors such as IS', the banks of which are multiplied with the banks of the drop-back selectors.

Having briefly described the lay-out of the 70 different offices shown in the drawings, the trunking between these offices will now be considered with a view to pointing out more clearly the various novel features. It is thought that the trunking can best be explained by considering certain typical calls 75 and tracing the establishment of the connections as they are set up.

The first call to be explained is a call from the substation A in the Midway office 80 to another substation, A' for instance, in the same office. The telephone number of substation A' may be assumed to be MIDway 1234. There is nothing new involved in a local connection of this kind, but it is 85 thought best to take up the simplest case first in order that the entire trunking scheme may be thoroughly understood from the beginning. Upon removal of the receiver at substation A, the line switch L⁴ 90 operates in the usual manner to select a trunk line extending to an idle first selector. Assuming that the trunk line extending to the first selector FS is the one taken for use, certain relays in the relay group RG 95 are energized and complete a holding circuit for the line switch L. At the same time a starting circuit is closed for starting a finder switch, such as F, which is associated with an idle director. Assuming that the director D is the one which is to be used, finder F operates and connects this director with the trunk line, extending the calling line through to the director so that the calling subscriber can set the register switches 100 therein and establishing a control circuit extending ahead over the trunk line to the first selector FS. The calling subscriber now operates his dial in accordance with the three letters MID of the telephone number 105 of the desired station, and then in accordance with the four digits of such number. The letters MID, which are equivalent to the digits 515, are registered by office registering equipment in the director, while the 110 four digits of the number are registered on digit registers in the director. As soon as the office registration is completed, a sender switch in the director starts to send out the several series of impulses which are necessary to control the office selectors in order to trunk the call to the desired office, which in this case is the local or originating office. It will be necessary, therefore, to trunk the 115 call to an idle thousands selector in the Midway office. As is well understood, the sender in the director is controlled in accordance with the setting of the office registering apparatus. Any particular office registration 120 can be made to cause the transmission of any 125 130

desired number of series of impulses, the impulses in each series being also of any desired number. The translation of the office designation into the several series of impulses for controlling the inter-office trunking, known as the office code, is effected by means of a distributing frame in the director, which enables the office code to be readily changed whenever it is necessary or 10 desirable to do so.

Proceeding with the call under consideration, an inspection of the drawings will show that in order to trunk the call to a thousands selector, such as the selector T 15 in the Midway office, the first selector FS will have to be operated to the second level, after which a second selector such as SS will have to be operated to the fifth level. The local office code for the Midway office, 20 therefore, is 25, and it will be understood now that when the office designation of the number is registered in the director D, the sender in such director immediately proceeds to transmit a series of two impulses 25 to operate the first selector FS, followed by a series of five impulses to operate a second selector such as the second selector SS, resulting in the extension of the trunk through first and second selectors to an idle 30 thousands selector such as the selector T. The director now transmits the four digits of the number as they were registered, operating the selected thousands selector, a hundreds selector such as H, and a connector 35 such as C, to complete the connection to the desired station. On completing the transmission of all the digits in the called number, the finder switch F is released in order to free the director and the two sections of 40 the first selector trunk line are united at the relay group RG, thus finally completing the connection between the calling and the called station.

The next case which will be considered is 45 the case of a call from one office to a second office which is connected to the first office over direct trunks. A typical case of this kind is a call from Midway office to Main office. Assuming that the subscriber at station A in the Midway office desires to connect with a subscriber in the Main office, whose telephone number may be assumed to be MAIn 1234, upon removing the receiver at substation A, the calling line is 50 extended to an idle first selector such as FS, and an idle director is taken for use as before. The calling subscriber now operates his dial in accordance with the desired telephone number and the several letters and 55 digits called are registered in the director. In this case the office code into which the office portion of the number must be translated is 621, as may be readily ascertained by tracing the trunk route from the bank of the 60 first selector FS in the Midway office through

the incoming selector IS² and the second selector SS² in the Main office, to the thousands selector T'. As soon as the office portion of the number is registered, therefore, the director proceeds to transmit series of 70 impulses in accordance with the office code 621, the first digit of which raises the first selector FS to the sixth level. On finding an idle trunk in this level, which may be assumed to be the one terminating in the 75 secondary line switch L⁵, this line switch is operated to select an idle outgoing trunk to the Main office. We may assume that the trunk line shown is selected, whereby it follows that the secondary line switch will 80 stop on such trunk and extend the connection through the repeater R to the incoming selector IS² in the Main office. The next series of impulses transmitted by the sender 85 operates the incoming selector IS² to the second level, and such selector then automatically selects an idle second selector. Assuming that the second selector SS² is the one taken for use, this selector is then raised to its first level, responsive to the third series 90 of impulses in the office code, and then operates to select a trunk line leading to a thousands selector. We may assume that the thousands selector T' is the one selected. After having transmitted the office code, the 95 director then proceeds to transmit the four registered digits, which are effective to operate the thousands selector T', together with a hundreds selector and a connector 100 (not shown) in order to complete the connection to the desired called station.

Having described briefly the setting up of local calls and inter-office calls to offices provided with direct trunks, we may now proceed to a consideration of the more complicated cases which involve tandem trunking. The first call of this general type which will 105 be considered is a call which involves tandem trunking over a single route and through one tandem office. A call from the Midway office to the North office is a call of this kind, and the process of setting up such call will now be briefly explained. Assuming that the subscriber at station A desires to call telephone number NORth 110 1234, and that the same apparatus in the Midway office is used as in the preceding cases, when the subscriber dials the desired 115 number the office portion of the number and the several digits are registered in the usual way. The directors in the Midway office are so cross connected that the office designation NOR (602) is not translated, the office code in this case being the same as the numerical 120 equivalent of the letters in the office designation. This, of course, is an unusual case but one which might well occur. When the office code 602 is transmitted by the director, 125 selectors FS in the Midway office, IS² in the Main office, and IS⁵ in the North office are 130

operated, with the result that the connection is extended to an idle thousands selector in the North office such as the thousands selector T^2 . It is noted that a secondary line switch L^6 is shown as being inserted between the incoming selector IS^2 and the repeater R' in the Main office. This arrangement is similar to the arrangement shown in connection with the first selector FS and needs no special consideration. The connection having been extended as far as the thousands selector T^2 in the North office, it will be readily understood that, as in the preceding cases, the remainder of the connection is established by operating such thousands selector, a hundreds selector, and a connector in accordance with the registered numerical digits of the called telephone number.

Before proceeding to the next case, it may be well to call attention to the office code used to trunk calls from the Midway office to the South office. As explained in the preceding case, the office code for the North office, considering the directors in the Midway office, comprises only three digits, but the office code for the South office comprises four digits, as the trunking in the South office is so arranged that two switches instead of one have to be operated in that office in order to connect with an idle thousands selector. To determine the office code, the trunking connection may be traced from the sixth level of the first selector FS in the Midway office, by way of the eighth level of the incoming selector IS^2 in the Main office, tenth level of the incoming selector IS^8 in the South office, and fifth level of the second selector SS^4 in the South office, to the thousands selector T^3 .

The next case which will be considered is a call which involves trunking over a single route through two tandem offices. A typical call of this class is one from a station in the Midway office to a station in the East office, such call being trunked through the Main and North tandem offices. In view of what has been said before, the operations performed in trunking the call to the desired office will not need any explanation except to point out the trunk route which is taken, as this route determines the office code for which the directors in Midway must be cross-connected in order to trunk the calls from Midway to East over the route such calls are intended to follow. By examining the drawing, it will be seen that a call to East office from Midway is first trunked to the Main office by raising a first selector, such as selector FS , to the sixth level. From the Main office the call is trunked to the North office by operating an incoming selector, such as IS^2 , to the tenth level. The call being now extended to an incoming selector, such as IS^5 , in the North office, it is extended to the East office by raising such incoming selector

to the third level. On this level are terminated trunk lines such as the one shown extending through the repeater R^5 to the incoming selector IS^{12} . The desired office having been selected, the call is finally extended to a thousands selector in the East office by raising the incoming selector IS^{12} to its third level, which is the level in which the thousands selectors, such as T^5 , are terminated. From the foregoing it will be understood that in the Midway office the office code for the East office is 6033, that is, when any subscriber in Midway office calls a number in the East office the office designation EAS (623) is translated by the director in use into the office code 6033.

Having explained several typical cases of tandem trunking over single routes, tandem trunking over alternate routes will next be considered. Calls from Midway to East will be used as an example. As described in the last case, these calls may be routed to the East office via the Main and North tandem offices. Another route, however, is equally available, this alternative route being by way of the Main and South tandem offices. The office code for the East office at the Midway office may well be 6823 instead of 6033. Assuming that the directors in Midway are cross-connected to translate the East office designation into the office code 6823, a call to the East office would be progressed to its destination by operating the first selector FS to the sixth level and an incoming selector such as IS^2 to the eighth level, resulting in the extension of the call to the South office. From this point it is further extended to a thousands selector in the East office by operating an incoming selector such as IS^8 in the South office to the second level and by operating an incoming selector such as IS^{12} in the East office to the third level.

The subject of alternative trunking is a very extensive one and no attempt will be made herein to discuss it exhaustively. A few advantages may be pointed out, however, in order that its utility may be somewhat appreciated. One great advantage in the provision of alternative trunk routes between two exchanges is that it prevents service from being entirely interrupted between such exchanges in case one of the routes should become incapable of handling traffic, due possibly to damage to some of the exchange equipment concerned, or to damage to an inter-office trunk cable. The latter trouble is perhaps the most likely to occur. To illustrate this, it may be assumed that all the traffic from the Midway office to the East office is normally routed by way of the Main and North tandem offices. If it be assumed now that the inter-office trunk cable for handling traffic from the North office to the East office is damaged and ren-

dered incapable of handling calls, then the cross-connections in the directors in the Midway office could be changed so that all of the calls will be routed to the East office by way of the Main and South tandem offices. Such re-routing of the traffic may, of course, overload the group of trunks extending from Main to South and the group of trunks extending from South to East, especially during the periods of peak load, but during the majority of the time the groups of trunks involved will handle most of the traffic and complete interruption of service between the exchanges concerned is prevented.

As assumed above, all calls from Midway to East may be normally routed by way of the North office, the alternative route through the South office being used only in case the route by way of the North office is interrupted for some reason. So long as the alternative route is provided, however, it is better to normally route part of the traffic by way of the North office and part by way of the South office, because if this practice is followed, when service is interrupted over either one of the routes only part of the total amount of traffic will have to be diverted to the remaining route. Thus there will be less danger of the remaining route being disastrously overloaded. In addition a slight increase in efficiency will be had in most cases. It is desirable to have each group of trunks handle calls to as many different exchanges as possible because the peak load to the different exchanges usually occurs at different times, and if traffic to a number of different exchanges is handled on a single group of trunks the load on the entire group will be better distributed.

The required division of traffic is accomplished by cross-connecting part of the directors in the Midway office so that they will translate the East office designation into the office code 6033 and by cross-connecting the remaining directors in the Midway office so that they will translate this office designation into the office code 6823. If it is desired to divide the traffic equally, one-half the directors in Midway will be cross-connected one way, and one-half the other way. Any desired portion of the traffic can, of course, be diverted to either the North or South offices by suitable changes in the number of directors that are cross-connected one way or the other, and since quite a large number of directors are involved as fine a division as is necessary or desirable can easily be obtained.

The proportion between the calls that are trunked via North and those that are trunked via South can be changed at any time to meet changes in traffic conditions.

Assuming that to start with half the calls are routed via North and half via South, it

may happen for some reason or other that the traffic from Main to North will increase, resulting in overloading of the group of trunks from Main to North, which carry not only the traffic from Main to North but also part of the traffic from Midway, Main, and perhaps other exchanges, to East. In order to alleviate this condition a few of the directors in Midway or in Main or in some other exchange which route traffic to East by way of North can be re-cross-connected so that they route traffic to East by way of South, thus evening up the load on the trunk groups involved.

Numerous other cases will arise in which slight shifts in the traffic routing can be brought about to good advantage in order to relieve temporary conditions of overloading on certain groups of inter-office trunks. One case in particular may be pointed out which is interesting inasmuch as it involves two shifts in the traffic routing, the second of which is made necessary or advisable in order to relieve overloading caused by the first. In the case previously referred to, where service over the inter-office trunk cable from North to East became interrupted, it was pointed out that all the traffic to the East office from the Midway office (also from Main office and other offices using the trunk route via North) could be routed by way of the South office in order to prevent total interruption of service. It would naturally be expected that this shift in the traffic routing would result in an overloading of the trunks from Main to South and perhaps from South to East also. The overloading of the trunks from Main to South can be relieved somewhat under these circumstances by re-routing part of the traffic from Midway, Main and other offices to South office by way of the North office. This traffic is all normally handled over the group of trunks from Main to South, but as stated, part of it may be routed by way of the North office. Calls progressed over the new routing would be established by way of the tenth level of incoming or second selectors in the Main office, the fifth level of incoming selectors such as IS⁵ in the North office, and incoming selectors IS¹¹ in the South office, the banks of which are multiplied with the banks of the thousands selectors in the South office.

Situations will arise where the directors can be divided along special lines to advantage in order to direct the traffic to distant offices over alternate routes. For instance there may be some reason for routing a particular class of calls over one route while calls of another class take a different route. Considering calls from Midway to East again, a part of these calls may be toll or pay station calls, and if the trunk cables involved in the route via North office are of

- heavier gauge or shorter in length than the cables involved in the route via South office, it will be desirable to route such toll or pay station calls by way of the North office rather than by way of the South office. This is easily accomplished by so cross-connecting the particular group or groups of directors in the Midway office which handle the toll and pay station calls so that they will trunk 5 all calls to the East office by way of North office, while all or most of the other directors are so cross-connected that they will trunk calls to East office by way of the South office.
- 15 The traffic may also be divided in accordance with the location of the originating station, since if this station is at a somewhat remote point, the call should obviously be routed to its destination by way of the best and shortest route. Considering calls 20 originating at the Midway office and at the Riverside sub-office for example. These calls are all handled by the directors in the Midway office, but those calls which originate at Riverside obviously should be given the best route because of the added trunk cable involved. If there is any choice between the routes through the North and South offices, therefore,—that is, if one of 25 these routes is better than the other,—the particular group of directors in Midway which handle calls from Riverside should be cross-connected so that they will route the traffic to the East office by way of the best 30 route.
- Only a few examples of alternative trunk routes are given in the foregoing. An examination of the drawings will show that a great many more possibilities exist. Calls 35 from Main to North may be routed direct or by way of South; calls from North to South may be routed direct or by way of East; calls from East to South may be routed direct or by way of North; calls from 40 East to Main may be routed by way of North, while calls from East to Midway may be routed by way of South, etc. And this is based on a consideration of only a very few offices taken from a large net-work.
- 45 When it is recalled that there will be numerous other offices located in different directions from the offices shown in the drawing, all of which offices are inter-connected by trunk lines, the great number of variations in the traffic routings that are possible will be appreciated. In certain cases it may be possible to progress a call from a given office to its destination over as many as half a dozen alternative routes.
- 50 Some further consideration may now be given to the allocation of the groups of outgoing trunks to the different levels in the banks of the first and second office selectors, and to the multiplying between the 55 office selector banks and the incoming se-
- lector banks. As mentioned hereinbefore, trunks to heavy tandem offices are taken from a level in the first selector banks rather than from a level in the second selector banks wherever possible, as shown in the 60 case of the trunks extending from the Midway office to the Main tandem office, which come from the sixth level of the first selectors. The reason for this is because it reduces the maximum number of digits in 65 the office codes that are required to trunk calls to different offices through the tandem office. In the case mentioned, that of the trunks from Midway to Main, the code for trunking a call through the Main office to 70 the East office comprises only four digits, whereas if the trunks from Midway to Main were taken from the banks of the second selectors such as SS then such code would necessarily comprise five digits. While the 75 directors can be made to transmit any desired number of code digits, it is desirable, of course, to keep the maximum number that they have to transmit as low as possible in order to save on the first cost of the directors. In addition, it is desirable to set up 80 a connection with as few switches or links as possible in order to save on the first cost of the switches, and in order to minimize the liability of trouble and increase the quality 85 of the established talking circuits. The fewer links that are involved in any connection the less probability there is of something going wrong while such connection 90 is being set up and the better the circuit 95 will be after it is established.
- The multiplying between the banks of the incoming selectors in the tandem offices and the office or thousands selectors in such tandem offices is also arranged with a view to 100 economizing on the maximum number of digits in the office codes involved. In order to explain some of the expedients that can be availed of in order to accomplish something in this direction the arrangements illustrated in the drawings may be explained 105 a little more in detail. Considering the trunks from Midway to Main, for instance, one might ordinarily expect that the incoming selectors such as IS² in which these 110 trunk lines terminate at the Main office would have their banks multiplied to the banks of the first selectors such as FS¹. This would in fact be necessary if the incoming selectors in question had to have access to all the different groups of trunks 115 outgoing from the Main office. In the present case, however, it is assumed that all of the traffic that comes in to the Main office from the Midway office over this group 120 of trunks is intended either for the Main office itself or for offices which are reached by way of the particular group of second 125 selectors including the second selectors SS¹. Disregarding for a moment the fact that 130

part of this traffic is intended for the Main office, the foregoing assumption makes it evident that the banks of the incoming selectors IS^2 can be multiplied with the banks 5 of the second selectors SS^2 instead of with the banks of the first selectors FS' , thus requiring only one digit instead of two digits to trunk a call through Main office to a point beyond. Similarly, it is assumed that 10 the traffic incoming to the Main office over the group of trunks which terminate in incoming selectors such as IS^3 and IS^4 is intended either for the Main office or for offices which are reached by way of the particular group of second selectors in Main office which includes the second selector SS^2 . Such being the case the banks of the incoming selectors IS^3 and IS^4 may be multiplied to the banks of the second selectors 15 SS^2 rather than with the banks of the first selectors FS' . This arrangement likewise saves a digit in trunking a call through the Main office. It will be noted that the second selectors SS^2 have access to the local 20 thousands selectors in the Main office such as T' , so that the incoming selectors IS^3 and IS^4 , whose banks are multiplied with the banks of the second selectors SS^2 , will also have access to such thousands selectors. 25 In the case of the incoming selectors IS^2 , however, access to such thousands selectors would be barred were it not for special provisions, and certain situations might arise in which the incoming selectors IS^2 would 30 have to be multiplied with the first selectors FS' in order to give them access to the thousands selectors in question. In the actual case under consideration, however, it is assumed that there is a vacant 35 level in the banks of the second selectors SS' which is not in use for outgoing trunks. This being the case, the corresponding level will be vacant in the banks of incoming 40 selectors IS^2 and can be used for trunking from such incoming selectors to the group of second selectors SS^2 . In other words, the group of second selectors such as SS^2 is made accessible from the first level of the first selectors such as FS' and also from the second level of the group of incoming 45 selectors which include IS^2 and the necessary access had while still obtaining the maximum economy in office digits.

In view of the foregoing, it will be understood that each group of incoming selectors in each office is multiplied with the particular order of switches which will give access to all required points, and that no more orders of switches are included than is absolutely 50 necessary. In the case of the trunks from the North office to the South office, a still greater economy is possible than in the case previously discussed. It is assumed that in 55 this case the trunks in question handle only traffic from the North office to the South

office, which makes possible the multiplying of the banks of the incoming selectors such as IS^{11} with the banks of the thousands selectors such as T^3 . It will be observed from this that while the South office is a tandem 70 office for certain connections, as on a call from Main to East or from Main to South, it is not a tandem office for calls from North to South. In the case of a call from Main to South or from Main to East the mere 75 trunking of the call to the South office does not finally determine its destination but one or more additional switches have to be operated before a thousands selector in the required office can be reached. In the case of 80 calls from North to South, however, the trunking of the call to the South office finally determines that the call is destined for the South office and the incoming selector operates as a thousands selector. 85

Another non-standard arrangement is shown in the case of the trunks from the South office to the East office, which trunks are accessible from the second level of the first selectors such as FS^3 , and also from the 90 third level of the second selectors such as SS^4 . The reason for multiplying these trunks to the banks of the second selectors SS^4 is to enable the incoming selectors such as IS^9 to be multiplied with this group of 95 second selectors rather than with the first selectors such as FS^3 . It is assumed, of course, that the incoming selector such as IS^9 handles traffic which is intended only for the South office and other offices reached by way 100 of the second selectors such as SS^4 , with a single exception of calls to the East office, which office is ordinarily reached by way of the first selectors in the South office. By multiplying the trunks in question in the 105 banks of the second selectors SS^4 also, this single exception can be taken care of.

The handling of calls at the sub-office at Riverside will next be considered and an explanation will first be made of the process 110 of extending a connection from the Midway office to the Riverside sub-office. The directors in Midway are cross-connected so that they will translate the office designation RIV (216) into the office code 25, which is the same as the office code into which the office designation MID (515) is translated. In establishing a connection extending from Midway to Riverside, therefore, the director 115 in use will operate a first selector such as FS to the second level and a second selector such as the second selector SS to the fifth level, resulting in the connection being extended to a thousands selector such as T . The thousands digit of the number is now transmitted, which raises the selected thousands selector to the fifth level, it being recollected 120 that the fifth thousand is the one that is assigned to the Riverside sub-office. The thousands selector then selects a trunk on 125 130

this level which extends direct to the Riverside sub-office and there terminates in an incoming selector such as IS'. The incoming selectors such as IS' have their banks connected in multiple with the hundreds selectors DH, from which it follows that the transmission of the three remaining digits will operate the incoming selector and a connector such as C' in the required group to finally complete the connection to the required station in the sub-exchange.

It will be noted that in establishing a connection as described above the office code does not actually determine to which office the call is going, this determination being made by the thousands selector in use in the Midway office. The reason for taking the trunks to Riverside from the banks of the thousands selectors in Midway instead of from the banks of a group of office selectors in such office may be questioned, since it introduces an additional link in the connection. For instance if these trunk lines were taken from the banks of the second selectors SS the thousands selectors T would be entirely by-passed and a shorter route would be obtained. If this were done, however, it would use up a level at the office selectors such as SS which might otherwise be necessary for trunking to some main office, that is, there may be no level available in any group of office selectors, whereas on the assumption that Riverside is a sub-office subsidiary to the Midway office it inherently follows that there will be a level available in the thousands selectors in such office. In addition, if the trunk lines to Riverside were to be selected by office selectors in the Midway office the incoming selector such as IS' at Riverside would have to be of the drop-back variety, as will appear hereinafter. With the arrangement illustrated, these selectors may be ordinary selectors. Another good reason for the arrangement shown is the fact that it permits the incoming selectors such as IS in the Midway office to be multiplied with the thousands selectors such as T. These incoming selectors handle traffic to the Midway office and also to the Riverside sub-office. If the trunks to the Riverside office were taken from the banks of some group of office selectors in Midway then these incoming selectors would have to be multiplied with such group of office selectors. This would introduce an additional link in all calls incoming to the Midway office from the Main office and points using the Main office as a tandem office for trunking to Midway, which would probably more than outweigh the advantage secured in cutting out a link in trunking calls from the Midway office to the Riverside sub-office.

Calls originating at the Riverside sub-office are handled by means of switching

selector repeaters as will now be explained. Assuming that the subscriber at station A² desires a connection with subscriber at substation A in the Midway office, he will remove his receiver and dial the desired number, which may be MIDway 1214. Upon removal of the receiver the line switch L⁴ operates and selects a trunk line extending to an idle switching selector repeater. Assuming that the switching selector repeater SSR is taken for use the secondary line switch L² immediately operates and selects an idle trunk extending to the Midway office, which may be the trunk shown in the drawing as terminating in the line switch L'. This latter line switch now operates also and selects a trunk leading to an idle first selector in Midway. Assuming that the first selector FS is taken for use a circuit is completed at the relay group RG by means of which an idle director such as D is connected to the trunk line by means of a finder such as F. On dialling the first digit of the number the switching selector repeater SSR is raised to the fifth level and at the same time impulses are repeated over the trunk line to the Midway office and the digit is registered in the director D. Since the first digit dialled, the digit 5, has definitely determined that the call is not intended for the Riverside sub-office, the switching selector repeater SSR remains standing opposite the fifth level and does not further respond to the operation of the calling device at the calling station but merely acts as a repeater. The remaining digits of the number, therefore, including the two digits 1 and 6 of the office designation and the numerical digits 1, 2, 1, and 4, are repeated over the trunk line to the director in use and are registered therein precisely the same as though the call was originated by a subscriber in the Midway office. It will be understood, therefore, that the director will trunk the call to a thousands selector such as T by translating the office designation into the necessary code, after which it will operate such thousands selector, a hundreds selector such as H, and a connector such as C, to complete the connection to the desired called station.

A call from station A² in the Riverside sub-office which is intended for a local station in the sub-office is completed locally as will now be explained. Assuming that the telephone number of the desired local station is RIVerside 5678, when the subscriber at station A² removes his receiver the switching selector repeater SSR may be taken for use as before responsive to the operation of the line switch L⁴. The secondary line switch L² now operates, followed by the operation of a line switch such as L' associated with the selected trunk, resulting in the selection of an idle first selector such as FS.

Following this, a director such as D is associated with the trunk line in use as pointed out hereinbefore. On dialling the first letter of the office designation, which corresponds to the digit 2, the switching selector repeater SSR is raised to the second level. Since the digit 2 is part of the office designation of the Riverside office, provision must be made for further operation of the switching selector repeater, and the switching selector repeater, therefore, is provided with shaft springs which close on the second level in order to prepare the switching selector repeater for response to the second digit. On the calling subscriber dialling the second digit the switching selector repeater SSR is rotated one step and since this second digit is also part of the office designation of the Riverside office, the switching selector repeater must be prepared for operation responsive to the third digit. The circuits are so arranged, therefore, that when the switching selector repeater SSR stops on the first set of contacts in the second level, it is released and restored to normal. On the calling subscriber dialling the third digit of the office designation, the digit 6, the switching selector repeater raises its wipers to the sixth level, and immediately starts to hunt for an idle trunk on this level. It may be assumed that the trunk line extending to the hundreds selector DH is selected. While the switching selector repeater was operating in accordance with the three digits in the office designation, it will be understood that impulses were simultaneously transmitted to the director D in the Midway exchange, where they were registered in the usual manner. Following the operation of the switching selector repeater SSR responsive to the third digit of the office designation, however, the trunk line to the Main exchange is released and all the apparatus therein is restored to normal. The calling subscriber now dials the thousands digit of the desired number, or the digit 5. Since this digit is of no utility, the call being a local one, it is absorbed by releasing the selector DH as soon as it is raised to the fifth level responsive to the thousands digit. As mentioned hereinbefore, the selector DH is a so-called "drop-back" or digit-absorbing selector, and its circuit is such that when it is raised to the fifth level it will restore to normal, its circuit being altered, however, consequent upon its release so that it may subsequently be raised to any level for the purpose of selecting an idle trunk in such level. It will be understood now that by calling the last three digits of the desired number, the hundreds selector DH and a connector such as C' are operated to finally complete the desired connection.

Attention is directed to the fact that although the Riverside sub-office is a thousand

line sub-office tributary to the Midway main office, the switching selector repeater SSR does not switch responsive to the calling of the thousands digit in a local number, but switches responsive to the calling of the last letter or digit in the office designation. In the ordinary switching selector repeater layout, the local or live level in the switching selector repeaters must necessarily be the level which corresponds to the particular thousand assigned to the sub-office, but in the present case the local or live level corresponds rather to the final digit in the office designation and may differ from the thousands digit assigned to the sub-exchange. This is so in the present case where the lines assigned to the Riverside sub-office are in the fifth thousand, the trunks coming from the Midway office being taken from the fifth level of the thousands selectors in such office, while the live level in the banks of the switching selector repeater SSR is the sixth level.

The principal advantage gained by handling sub-office traffic as described in the foregoing is that a sub-office may be changed to a main office at any time without having to change any of the subscribers' telephone numbers. For instance, the Riverside sub-office in the lay-out illustrated can be changed to a main office with a capacity of a full ten thousand lines by merely adding the necessary switches and re-arranging the trunking without changing any telephone numbers whatever, this re-arrangement being at the same time effective to release the fifth thousand at the Midway office for use at that office, making the Midway office a full ten thousand office also.

The changes necessary in order to convert the Riverside sub-office into a main office may be briefly pointed out, as a modified type of conversion is possible which might not be readily apparent from what has preceded. If a full conversion is desired, that is, if the Riverside exchange is to have the full status of a main office, there is nothing about the conversion that will need any particular explanation, because the resulting exchange will be similar to those already depicted. In view of its location in the lay-out the full main office lay-out at Riverside would probably be somewhat similar to what is shown in connection with the East office. It is possible, however, to operate the Riverside exchange as a main exchange so far as incoming traffic is concerned, with a capacity of a full ten thousand lines, while it continues to operate as a sub-office so far as the outgoing and local calls are concerned. In order to accomplish this result thousands selectors are inserted between the switching selector repeaters such as SSR and the hundreds selectors such as DH, the drop-back feature of the latter switches being elimi-

nated. In addition the incoming selectors such as IS are multiplied with the newly added thousands selectors instead of with the hundreds selectors. At the Midway office the only change that is necessary is to shift the trunks to Riverside from the fifth level of the thousands selectors such as T to some level of a group of office selectors, the group of office selectors which includes selector 10 SS for example. This is the only change required provided direct trunks are installed between Main and Riverside, but if the Midway office is to serve as a tandem office for trunking to Riverside then the incoming selectors such as IS will, of course, have to be multiplied with the second selectors such as SS instead of with the thousands selectors as shown at present. An arrangement of this kind may prove to be economical even in the case of a main office which is being installed such as the beginning. It results in a concentration of all the directors for two offices at one point and since the directors serve twice the ordinary number of lines it will be easier to secure large and efficient groups.

Having described my invention, what I consider to be new and desire to have protected by Letters Patent will be pointed out in the appended claims.

What is claimed is:

1. In a telephone system, a first office, a second office, two intervening tandem offices, directors in the first office arranged to trunk calls to the second office via the first tandem office, and other directors in the first office arranged to trunk calls to the second office via the second tandem office.

2. In a telephone system, a first office, a second office, two intervening tandem offices, a group of directors in said first office common to a plurality of lines terminating in such office, said directors comprising means for trunking calls from said lines to the required offices, circuit connections in certain of said directors providing for trunking calls from said lines to said second office via one of said tandem offices, and different circuit connections in the remaining directors providing for trunking calls from said lines to said second office via the other tandem office.

3. In a telephone system, a first office, a second office, two intervening tandem offices, directors in the first office for controlling the extension of calls from the first office to the second office through said tandem offices, and means in said directors for trunking calls of a certain class to said second office via the first tandem office while calls of another class are trunked to said second office via said second tandem office.

4. In a telephone system, a first office, a second office, two intervening tandem offices, lines terminating in said first office, trunks

terminating in said first office, a group of directors in said first office for trunking calls from said lines to said third office via one of said tandem offices, and another group of directors in said first office arranged to trunk calls coming in over said trunks to said second office by way of the other tandem office.

5. In a tandem office, first office selectors, second office selectors accessible to said first office selectors, thousands selectors accessible to said second office selectors, incoming selectors having their banks multiplied with the banks of said first office selectors, other incoming selectors having their banks multiplied with the banks of said second office selectors, and other incoming selectors having their banks multiplied with the banks of said thousands selectors.

6. In a tandem office, office selectors, thousands selectors accessible to said office selectors, incoming selectors having their banks multiplied with the banks of said office selectors, and other incoming selectors having their banks multiplied with the banks of said thousands selectors.

7. In a tandem office, first office selectors, second office selectors accessible to said first office selectors, incoming selectors having their banks multiplied with the banks of said first office selectors, and other incoming selectors having their banks multiplied with the banks of said second office selectors.

8. In a tandem office, office selectors, local selectors accessible to said office selectors, incoming selectors in two groups coming from two different outlying offices, respectively, a multiple between the banks of said office selectors and the banks of one group of incoming selectors, and a separate multiple between the banks of said local selectors and the banks of the other group of incoming selectors.

9. In a tandem office, first office selectors, a group of second office selectors accessible to said first office selectors, incoming selectors having their banks multiplied with the banks of said second office selectors, and a second group of second office selectors accessible to said first office selectors, said second group of second office selectors being also accessible to said incoming selectors.

10. In a tandem office, first office selectors, second office selectors accessible to said first office selectors, incoming selectors having their banks multiplied with the banks of said second office selectors, and a group of trunk lines multiplied in the banks of all said selectors.

11. In a telephone system, a main office, a sub-office, switching selector repeaters in said sub-office arranged to handle local calls and to repeat the digits involved in inter-office calls to the main office, and directors in the main office arranged to handle calls

originating in the main office and also all interoffice calls originating in the sub-office.

12. In a sub-office, switching selector repeaters accessible to the subscribers' lines, 5 digit absorbing selectors directly accessible to said selector repeaters, and connectors accessible to said selectors.

13. In a sub-office, switching selector repeaters accessible to the subscribers' lines, 10 digit absorbing selectors directly accessible to said selector repeaters, connectors accessible to said selectors, and incoming selectors having their banks multiplied with the banks of said selectors.

14. In a sub-exchange, subscribers' stations having telephone numbers each comprising a plurality of letters and four digits, switching selector repeaters in said sub-office arranged to switch responsive to the 20 last letter in a local telephone number, selectors in said sub-office adapted to absorb one of the digits in such telephone number and operate responsive to another, and connectors in the sub-office responsive to the last 25 two digits.

15. In a telephone system, a main office, a sub-office, trunks extending from local selectors in the main office to incoming selectors in said sub-office, whereby the capacity 30 of the main office is limited to an extent depending on the size of the sub-office, lines in the main office having numbers which include an office designation derived from the exchange name, and lines in the sub-office 35 having numbers including a different office designation derived from the name of the sub-office.

16. In a telephone system, a main office, a combination main office and sub-office, office 40 selectors in said main office, trunks extending from the banks of said office selectors to incoming selectors in said combination office, switching selector repeaters in said combination office for handling local calls and for 45 repeating trunked calls to said main office, and directors in said main office for handling calls originating in the main office and the calls which are trunked to such office from the combination office.

17. In a telephone system, a first office, a second office, directors in said first office for trunking calls from said first office to said second office in accordance with office codes, there being two such codes which may 55 be used, one code comprising more digits than the other, and circuit connections in said directors such that part of the said directors will use one code while other directors will use the other code.

18. In a multi-office telephone system, a tandem office, two trunk line groups outgoing from said tandem office to two other offices, respectively, two incoming trunk line groups, automatic switches operable to extend 65 connections from one incoming trunk

line group to only one of said outgoing groups and operable to extend connections from the other incoming group of trunk lines to both of said outgoing trunk line groups.

19. In a multi-office telephone system including telephone offices each designated by the same number of characters as any one of the others, one of said offices being a tandem office, two outgoing trunk line groups outgoing from said tandem office to two other of said offices, respectively, two trunk line groups, incoming to said tandem office, and automatic switching mechanism in said tandem office operable to extend connections from one incoming trunk line group to only one of said outgoing groups and operable to extend connections from the other incoming trunk line group to both of said outgoing trunk line groups.

20. In a multi-office telephone system as claimed in claim 19, a third incoming trunk line group, said automatic switching mechanism being operable to extend connections from said third incoming trunk line group to telephone lines terminating in said tandem office, but not to either of said outgoing trunk line groups.

21. In a multi-office telephone system including a plurality of main offices, a sub-office subsidiary to one of said main offices, the lines of said sub-office having assigned thereto numbers displacing a block of numbers of said main office, each of said offices having assigned thereto a designated separate and distinct from the designation of every other one of said offices, and switching apparatus controlled in accordance with the office designation of the sub-office when a call to the sub-office is being made and controlled in accordance with the office designation of the associated main office when a call to the main office is being made for extending the connection to the main office in both cases.

22. In a multi-office telephone system including a plurality of main offices, a sub-office subsidiary to one of said main offices, the lines of said sub-office having assigned thereto numbers displacing a block of numbers of said main office, each of said offices having assigned thereto a designation separate and distinct from the designation of every other one of said offices, inter-office-trunking switches controlled in accordance with the office designations of the respective offices, numerical switches controlled in accordance with the remaining portions of the subscribers' numbers, and means for operating the inter-office-trunking switches in the same way whether a call is for said sub-office or for its associated main office for trunking the call to one of the numerical switches in the main office.

23. In a multi-office automatic telephone

system, three offices, inter-office trunking arrangements so that a connection from one office may be completed to either remaining office by way of the other, and means 5 including translating apparatus in the calling office for causing calls to be completed either way.

24. In a multi-office automatic telephone system, a calling office, three other offices, 10 inter-office trunking arrangements such that a call to any one of said other offices from said calling office may be completed by way of the other two of said other offices, and means including translating apparatus in 15 the calling office for bringing about said routing.

25. In a multi-office automatic telephone system, four offices, inter-office trunking ar-

rangements so that calls from the first office may be completed directly to the second and 20 to the third offices, such that all calls from the first office to the fourth office must pass through either the second or the third called office, such that calls from said first office to either the second or the third office may 25 pass first through the other of the two offices, and such that calls from the first office to any one of the other offices may pass through the other two of said offices, and means including translating apparatus in 30 the calling offices for causing any one of said routings to take place.

In witness whereof, I hereunto subscribe my name this 6th day of March, A. D., 1925.

MARTIN L. NELSON.
